UNITED STATES PATENT OFFICE.

EMIL TANKE, OF FALKENHAGEN B/SEEGEFELD KREIS OSTHAVELLAND, GERMANY,
ASSIGNOR TO AUTOMATIC ELECTRIC COMPANY, OF CHICAGO, ILLINOIS, A COR-
PORATION OF ILLINOIS.

IMPULSE TRANSMITTER OF THE DIAL TYPE.

Application filed November 29, 1921. Serial No. 518,723.

To all whom it may concern:

Be it known that I, EMIL TANKE, a German citizen, and resident of Falkenhagen b/Seegefled Kreis Osthavelland, Germany, 5 have invented certain new and useful Improvements in Impulse Transmitters of the Dial Type, of which the following is a specification.

This invention relates in general to impulse transmitters for automatic or semi-automatic telephone systems and more particularly to impulse transmitters of the type in which sufficient time is gained for the operation of the automatic switches between 10 the transmission of each series of impulses by the provision of means for bridging the impulse springs and thereby rendering a definite number of current impulses ineffective. The means serving for the bridging 15 of the impulse springs has, so far as applicant is aware, heretofore been influenced by a special axially displaceable spur wheel.

A material simplification of the known arrangement is provided according to this 20 invention, by causing the contact serving for bridging the impulse springs to be controlled by the same member which is used to influence the contacts serving for controlling the line switching action.

30 A constructional example of the improved dial switch with the omission, however, of the parts not required for the understanding of the invention, is illustrated in the annexed drawing, in which Figure 1 shows a rear view of the dial switch and Figure 2 a detail thereof in lateral view. Rotatably journalled in the base plate 1 is a shaft 2 secured to which is the number disc provided with the usual finger holes. Arranged, 35 moreover, on the shaft 2, is a disc 3 provided on which are cams 4 and 5. Rotatable also on the shaft 2 is a lever 6 the free end of which carries a pin 7 and normally is in engagement with a pin 8 secured in the plate 1. The spring 10 has the tendency to draw the lever 6 towards the cam 4. The shaft 2 carries rotatably also a worm gear 11 which is provided with facial teeth 12. Engaging with these locking teeth 12 is a 40 pawl 13 arranged on the plate 1 and adapted to counteract a rotation of the worm wheel 11 in the direction of the setting action indicated by the lower arrow. In the return movement indicated by the upper arrow the

worm wheel 11 is rotated from the shaft 2 55 by means of intermediate mechanism not shown.

The worm teeth on the wheel 11 engage with a worm 16 secured on the braking shaft 14 of the centrifugal governor 15. The centrifugal governor 15 serves in a known manner for the regulation of the return movement of the finger hole dial under the influence of a cocked spring. In the position of rest of the dial switch the centrifugal 60 governor 15 is held fast by a cam 5.

Secured between the insulating plates 17 mounted on the base plate 1 is a set of contact springs. This set comprises the contact springs 18, 19 for the impulse contact 20, 70 the contact springs 21, 22 for the contact 23 serving for bridging the impulse contact 20 and the contact springs 24, 25, 26, controlling in a known manner the contacts 27 governing the line connections. As shown 75 in Figure 2, the contact springs 21, 22, are of angular shape so that the contact 23 is situated laterally with regard to the contacts 27. Secured to the governor shaft 14 is the wheel 28 serving for the opening of 80 the impulse contact 20. The transverse pin 7 on the lever 6 in the normal position of the dial switch acts on the spring 26 to hold the contact 27 open. In the normal position of the dial switch the contact 23 is 85 closed.

The operation of the dial switch above described is as follows:—

By the removal of the receiver by the subscriber, the finger hold dial is released. The 90 subscriber commences in known manner to rotate the finger dial down to a stop. The cam 4 on the disc 3 which partakes of the rotation of the finger dial, releases the lever 6 so that the latter, under the action of the 95 spring 10 follows the cam 4 until the pin 7 of the lever 6 encounters the abutment 9. At the commencement of the movement of the lever 6, the pin 7 releases the contact spring 26 whereby the contacts 27 for the line are 100 closed. At the end of the movement of the lever 6 the pin 7 acts against the contact spring 21, thereby opening the contact 23, bridging the impulse contact 20. In addition, the cam 5 on the disc 3 releases the 105 brake 15.

Now when the subscriber releases the finger dial, the latter, under the action of

the spring tensioned by the setting movement, returns to its initial position. In this movement the worm gear 11 is carried along by the mechanism, not shown, and transmits its movement by means of the worm 16 to the brake shaft 14, whereby the latter and the impulse wheel 28 secured thereto are rotated. During each rotation of the impulse wheel 28, the impulse contact 20 is interrupted once so that the impulses are produced from the commencement of the return motion of the finger dial. At the moment in which the finger dial has moved back so far that the cam 4 on the disc 3 connected thereto engages and moves along the lever 6, resting against the abutment 9, the contact spring 21 is released from the pin 7 and consequently the contact 23 is closed. As the contact 23 is connected in parallel with the impulse contact 20, the interruptions of the impulse contact effected during the remainder of the return of the disc 3, in which the lever 6 is moved to its initial position, are ineffective. At the end of the return movement of the lever 6 to the initial position, the contacts 27 are opened by the pin 7 striking against spring 26 and the position of rest is re-established.

By combining the contact springs 18, 19, 21, 22 and 24 26 to a set, separate connections between the individual contact springs are rendered superfluous.

What I claim and desire to protect by Letters Patent is:—

- 35 1. In an impulse sending device, a finger hold dial, impulse springs, springs for short circuiting said impulse springs, other springs for short circuiting substation apparatus, and a common member controlled by said dial for directly operating both sets of said short circuiting springs.
- 40 2. In an impulse sending device, interrupter springs, a pair of springs for short circuiting said interrupter springs, other springs, and a single means for operating said other springs during both the setting and impulse transmitting operation of said device and for operating said short circuiting springs only during the initial part of the setting operation and the final part of the impulse transmitting operation.
- 45 3. In an impulse sending device, interrupter springs, a pair of springs for short circuiting said interrupter springs, other springs, and a single means for operating said other springs during both the setting and impulse transmitting operation of said

device and for opening said short circuiting springs upon the initial part of the setting operation and only closing said springs during the final part of the impulse transmitting operation.

4. In an impulse sender having forward and backward movement, means for sending impulses on the backward movement, contacts closed during the forward and backward movement of the sender and other contacts closed only during a portion of the backward movement to render the impulse sending means ineffective, and a single member for operating both sets of contacts.

5. In an impulse transmitting device, interrupter springs, a pair of springs for short circuiting said interrupter springs, and means for rendering the said last springs effective during the final of a plurality of operations of said impulse springs.

6. In an impulse transmitting device, impulse springs, means for operating said springs a plurality of times each time the device is operated to transmit one or more impulses, and means rendered effective just prior to the final operation of said springs to render such operation ineffective so far as the transmission of an impulse is concerned.

7. In an impulse transmitting device, impulse springs, means for operating said springs a plurality of times each time the device is operated to transmit one or more impulses, and means rendered effective just prior to the final operation of said springs to render such operation ineffective so far as the transmission of an impulse is concerned, the said means comprising a pair of springs connected in multiple with said interrupter springs.

8. In an impulse transmitting device, impulse springs, a cam for separating said springs a plurality of times each time the device is operated, and means for maintaining said springs electrically connected during their final separation.

9. In an impulse transmitter, a finger hold dial, subscriber controlled mechanism for producing series of interruptions in the line circuit, an automatic device for rendering the last interruption of every series ineffective, said device comprising a pair of shunt springs and a bell crank lever for operating them, and means controlled by the said dial for operating said lever.

EMIL TANKE.
